UNITED STATES PATENT OFFICE.

WILMER J. ALTHOUSE, OF GIBRALTAR, PENNSYLVANIA.

NEEDLE BAR FOR KNITTING MACHINES.

Application filed May 22, 1926. Serial No. 110,883.

This invention relates to improvements in knitting machines and pertains more particularly to machines for knitting so-called flat fabrics, such as full fashioned stockings.

5 The object of the present invention is to provide a needle bar on which the entire stocking may be knitted, thus overcoming the necessity of removing the stocking when the leg portion is completed and placing it 10 on another machine, called a "footer" for knitting the foot portion.

To this end I have devised a needle bar made up of a plurality of sections, with suitable mechanism for moving one or more 15 sections with relation to the other sections, whereby the leg portion is first made, then the heel portion, and later the foot portion.

The invention is more fully described in the following specification and clearly illustrated in the accompanying drawings, in 20 which:—

Figure 1 is a plan view of my improved needle bar, showing the relative positions of the different sections, while knitting the 25 leg portion—the dotted position of the centre section showing in the position at the end of its movement.

Figure 2 is a front or elevational view thereof.

30 Figure 3 is a plan view showing the needle bar in the position it assumes after the heel portion has been knitted and while knitting the foot portion.

Figure 4 is a side view of Figure 2.

35 The needle bar is made up of five sections, comprising a central section 1, two end sections 2 and two auxiliary sections 3. The sections 3 lie normally below the line of the other two sections 2 and the central section 1.

The central section is provided with a screw 5 for drawing it forward with relation to the end sections 2, and this screw is rotated through any ordinary medium, as the 45 bevel gear 6, driven from any operating portion of the machine.

The end sections 2 are each slideable on a locking rod 8 and this rod passes through said sections and enters the central section, to the end that when they are alined for knitting, as shown in Figure 1, they are held in proper alinement. The end sections each have a pull bar 10 attached thereto, so that they may be drawn laterally away from the 55 central section 1.

The numeral 3 designates the two auxiliary bar members, and these members, as stated, lie normally below the horizontal line of the normal upper position of the needle bar.

These members 3 are each provided with elevating means in the form of a depending rod 14 and a cam 15, connected in any suitable manner with one of the reciprocating operative members of the machine on which it is used, so that the movement of the cams will raise the auxiliary members into knitting position, that is, in line with the other members 1 and 2.

These auxiliary members 3 are also adapted to be turned to a position at right angles to their normal position, as shown in Figure 1, and this mechanism consists of a sleeve 20 on which is a lug 21, connected through a bar 22 to a crank arm 24, which latter is actuated by a horizontally movable rod 26, which latter is also operated through any suitable movable portion of the machine, and, like the other movement of these members 3, timed to be raised when the central section 1 is at the full forward position.

Starting with the needle bar as shown in Figure 1, the leg of the stocking is knitted and when the heel portion is about to be begun, the central member 1 of the needle bar will have attained the position shown in dotted lines, Figure 1. At this point the auxiliary members 3 are raised, through the mechanism described for the purpose, and they will knit the two small sections that go to make up the heel. When this has been completed, the end members 2 of the needle bar, will be drawn away from their normal positions, through the action of the bars 10, and, at the same time, the rod 26 will actuate the crank arm 24 and bar 22 to turn the auxiliary members 3 and place them in alinement with the members 1 and 2, as shown in Figure 3.

From this point, the knitting will proceed and the remaining portion of the foot will be knitted.

When the stocking is completed, the movements above described will be reversed, and the relative parts of the needle bar returned to the starting positions, as disclosed in Figure 1.

As in all machines of this character, the yarn is of course fed to the needles by a carrier bar having an arm with three eyes

through which the yarn passes, one to each of the three banks.

In the present structure, the yarns to banks 1 and 2 are fed until the desired length is knitted, when the bar 8 is actuated to unlock the banks 1 and 2, while the bar 26 will actuate the screw 5, and the banks 2 will knit the heel. At this time the bank 1 is being drawn away from the machines 10 knitting line. When the desired length has been thus knitted, the members 15—14 are actuated to raise the banks 3 through the fabric, which is the inside of the heel. The machine then makes another turn and the 15 fabric is released from the banks 2 and the bar 10 enters into play to draw the banks 2 into horizontal position, to right and left of their former positions. During the turning of the machine, the bar 10 separates the banks 2 to the right and left, to make room for the banks 3 which are turned in an arcuate movement through the parts 20 21, 22, 24 and 26, and the screw 5 will bring the banks 1 and 3 forward to line up in a 25 straight knitting position.

The next turn brings the members 8 together to lock the banks 1 and 3 together and the machine continues to knit the foot on the leg of the stocking until the said foot 30 length has attained proper size at which time the carrier bar puts in the toe yarn and the machine continues to knit and finish the stocking on the banks 1 and 3, at which point the machine releases the finished fabric 35 product.

At this point, the one turn of the machine draws the bars 8 apart. On the second turn, the members 21, 22, 24 and 26 actuate to release and return the banks 3 to their 40 former or non-knitting position. The next turn actuates the bar 10 to bring the banks 2 into alinement with bank 1 and the bar

8 on each side is brought toward the opposing bar 8 to lock the banks 1 and 2 together, and the machine is ready to start knitting 45 another stocking. At this time also, the cam 15 permits the member 14 to drop and bring the bank 3 down out of the way of the knitting to be done.

Having thus fully described my invention, 50 what I claim and desire to claim is:—

1. A needle bar for knitting machines comprising a plurality of sections, one of which is movable forward with relation to the other sections, two of which are movable laterally and two of which are mounted for 55 vertical and a limited arcuate movement and all adapted to knit along the same straight line.

2. A needle bar for knitting flat fabric 60 comprising a central section, two end sections and two auxiliary sections, all adapted to knit along the same straight line, said central section being movable forward and back with relation to the end sections, the 65 end sections being movable laterally with relation to the central section and the auxiliary sections being movable vertically with relation to the central and end sections.

3. A needle bar for knitting flat fabric 70 comprising a central section, two end sections and two auxilliary sections, all adapted to knit along the same straight line, means for drawing the central section forward with relation to the end sections and means for 75 moving the end sections laterally with relation to the central section and means for raising the auxiliary sections into horizontal alinement with the end sections and moving them into knitting position and alinement 80 with the end and central sections.

In testimony whereof I affix my signature.

WILMER J. ALTHOUSE.
